FOUNDATION GARMENT

Mario Laguzzi, Long Island City, N.Y., assignor to
Poirette Corsets Inc., New York, N.Y.
Filed Jan. 12, 1962, Ser. No. 165,766
8 Claims. (Cl. 128—548)

This invention relates to a foundation garment such as a girdle or the like, and has as its primary object the provision of an improved garment of this nature characterized by diagonally disposed reinforcing bands having a reinforcing section integral with the adjacent section which it serves to reinforce.

A further object of the invention is the provision of a garment of this character wherein the front and back panels or, alternatively, the side panels, are provided with diagonal reinforcing bands with the panels so cut as to enable them to be folded back upon themselves together with their associated reinforcing bands in such manner as to provide diagonal reinforcement in an opposite direction at the points of greatest stress.

An additional and more specific object of the invention is the provision of a garment of this character wherein the front panel, illustratively, or the back and/or side panels, are cut from a single piece having one or more diagonally disposed elasticized reinforcing bands extending thereacross and provided with a fold line at an intermediate point of the panel, which when reverted back upon the panel, disposes the ends of the diagonal bands in a direction at an angle to the original bands, the two portions of the panel then being sewn together along the fold line.

A further and more specific object of the invention is the provision of a garment of this character which may be made simply, economically, and rapidly to provide a garment with a combination of reinforcing diagonal bands and a self-reinforcing elastic section.

A further object of the invention is the provision of a garment of this character provided with means for reinforcing not only the front of the garment but providing additional support throughout the rest of the garment by the placing of the bands either at the rear or on the sides as well as in the front.

A still further object of the invention is the provision of a garment of this character which is attractive in appearance, which provides maximum reinforcement at any or all of a plurality of desired points and which at the same time permits maximum freedom of movement to the wearer with maximum comfort and lack of binding.

Still other objects reside in the combinations of elements, arrangements of parts, and features of construction, all as will be more fully pointed out hereinafter and disclosed in the accompanying drawings wherein there are shown preferred embodiments of this inventive concept.

In the drawings:

FIGURE 1 is a front elevational view of one form of foundation garment constructed in accordance with the instant invention, the garment being turned inside out.

FIGURE 2 is an elevational view or plan of the inner side of one of the panels employed in the manufacture of the garment of FIGURE 1 shown before folding.

FIGURE 3 is an enlarged sectional view taken substantially along the line 3—3 of FIGURE 1 as viewed in the direction indicated by the arrows.

FIGURE 4 is a front view showing a modified form of construction.

FIGURE 5 is a plan view of one of the panels employed in the garment of FIGURE 4.

FIGURE 6 is a front view disclosing the reinforcing at the sides of the garment rather than the front.

2

FIGURE 7 is a plan view of one of the panels of the garment of FIGURE 6.

FIGURE 8 is a rear view of the garment of FIGURE 6.

5 FIGURE 9 is a plan view of one of the panels of the structure of FIGURE 8.

FIGURE 10 is a view similar to FIGURE 6 showing a still further modified form of garment wherein the reinforcing strips run in a different direction; and

10 FIGURE 11 is a plan view of one of the panels of the construction of FIGURE 8.

FIGURE 12 is a fragmentary plan view of a modified elastic band construction.

Similar reference characters refer to similar parts throughout the several views of the drawing.

Having reference now to the drawings in detail, and more particularly to FIGURES 1 to 3, inclusive, there is generally indicated at 20 a foundation garment constructed in accordance with the instant invention. The

20 garment comprises a pair of substantially identical elastic panels 21 and 22, the panels being substantially mirror images of each other. One of these panels 21 is disclosed in FIGURE 2. The panel 21 is formed with an arcuate side 23 to which is attached a similar or identical

25 rear panel. An inclined top edge 23' terminates in an offset portion 24 which includes an ornamentally designed arcuate projecting tongue 25 which terminates in an extremity 26 and then tapers as at 27 and 28 in a pair of curves to an arcuate upwardly inclined bottom edge

30 29. In this modification of the invention a pair of diagonally disposed elastic bands 30 and 31 extend respectively from a point 32 adjacent the side of the top edge to a point 33 adjacent the lower edge of arcuate section 27, and, in the case of band 31, from a point 34 adjacent the

35 top of the arcuate curved side edge to a relatively central point 35 in the middle of the curved edge 28. Suitable stitching 36 which may be of the zigzag variety extends along each edge of each band. A fold line 37 extends from a point adjacent the offset portion 24 on the top edge 23' in a straight line downwardly to a point 39 on the bottom edge 29. When it is desired to assemble the

37 garment, the tongue terminating in the extremity 26 is reverted along the fold line 37 so that the portions 30a and 31a of bands 30 and 31 extend diagonally in substantially perpendicular relation to the main body portions

40 30 and 31 of these panels, as best seen in FIGURE 1.

There is thus provided a center panel having cross reinforcement at the point of greatest stress, as for example, in the center of the abdomen in the case of the front

45 panel, as best shown in FIGURE 1. The two panels 21 and 22 are then stitched together along their juxtaposed fold lines 37, and the reverted portion terminating in the extremity 26 is sewn to the front of the body of the

50 garment in any desired conventional manner.

A suitable elastic top binding 40 may be provided in the conventional manner, as may a bottom binding 41, the latter being provided with the usual garter tabs 42. A garment constructed in accordance with the above disclosure may have a substantially solid elastic rear panel,

55 or of one piece, or of two pieces stitched together along a center line 43 (see FIG. 1) or, alternatively, may have a rear section which is constructed in an identical manner, the arrangement being such in this modification of the

60 invention that the diagonal reinforcing bands extend downwardly from a point substantially adjacent the top of the garment to the center of the front or rear as the case may be, and thence are reverted at their point of juncture with the corresponding bands of the opposite panel to extend in a diagonal downward and outward

65 direction to provide maximum reinforcement at the points of greater stress. Since the panels 21 and 22 are sub-

60 jects of the invention, the diagonal bands may be of any suitable width and may be continuous or discontinuous, as

65 may be desired. The bands may be of any suitable elastic material, such as spandex, and may be of any suitable

70 thickness, as may be required to provide the desired reinforcement. The panels 21 and 22 may be of any suitable

stantially identical except as above stated that they are mirror images, the same reference characters are employed on both panels in FIGURE 1.

FIGURES 4 and 5 disclose a modified form of the invention wherein a pair of opposite panels 50 are each provided with a pair of diagonally extending reinforcing bands 51 and 52 which extend beyond a fold line 53 to form portions 51a and 52a in a projecting tongue 54 which is reverted back along the fold line 53 in the same manner as the garment previously described. The distinction in this modification over that of the previous modification resides in the fact that in this modification the diagonal reinforcing bands extend from points toward the lower extremity of the garment around the hips upwardly toward the center of the abdomen and are then reinforced by the reversion of the diagonal strips in the same manner as that of the previously described modification. It may here be pointed out that the bands 30 and 31 and/or 51 and 52 may be positioned either on the external side of the garment or on the internal side of the garment. FIGURE 1, for example, shows the garment turned inside out with the reinforcing band sewn to the inner side, while FIGURE 4 shows the right side of the garment with the bands in their relative position being indicated in dotted lines.

FIGURES 6 and 7 show a still further modified form of construction wherein a garment 60 is comprised of two side panels 61, with an ornamental reinforcing design 62 positioned across the center line 63 where the panels are joined. In this case each side panel is formed with diagonal reinforcing strips 64 and 65 which extend beyond an arcuate fold line 66 as indicated at 64a and 65a onto a projecting tongue 67. The tongue 67 is reverted and sewn to the body of the panel 61, and rear side panels of identical configuration are sewn along the sides of the garment to the fold line 66. In this instance, the diagonal reinforcement afforded by the strips 63a and 64a is provided at the sides of the garment rather than at the front or rear as in the previously described modification.

FIGURES 8 and 9 disclose the construction of the rear panels of the garment of FIGURES 6 and 7, wherein the two rear side panels are joined along a line 70, and each rear panel comprises an elastic member 71 including two diagonally stitched reinforcing elastic bands 72 and 73 which have portions 72a and 73a projecting beyond the arcuate fold line 74 when folded. The position of the bands along the fold line is identical to that described in connection with FIGURES 6 and 7, and the fold lines 66 and 74 are secured together to provide an arcuate side portion with crossed reinforcing bands providing maximum support at the hips where in this instance such support is most desired.

FIGURES 10 and 11 show a construction similar to that shown in FIGURES 6 and 7 wherein two panels 80 are each provided with projecting tongues 81 which extend beyond the fold line 82. Diagonal bands 83 and 84 are provided with end portions 83a and 84a on the projecting tongue which is reverted in the same manner as that of the previously described modification. These panels are stitched together along a center line 85 provided with an ornamental reinforcement 86 as is conventional. In this modification of the invention it is to be noted that the bands extend upwardly from the bottom of the garment toward the center thereof, rather than downwardly toward the center in a diagonal direction as in the modifications of FIGURES 6 to 9. Obviously, the back

panels of this form of invention are identical to the front panels above described.

In FIGURE 12 there is disclosed a modified form of elastic bands which may be substituted for any of the bands 30, 31, 51, 52, 64, 65 or 83, 84. In this form of construction a slightly narrower band 90 is disposed diagonally across the panel of the garment 91 and is secured thereto by a single line of zig-zag stitching 92, rather than a separate band of stitching along each marginal edge of the band as in the previous modifications.

From the foregoing it will now be seen that there is herein provided an improved foundation garment which accomplishes all the objects of this invention, and others, including many advantages of great practical utility and commercial importance.

As many embodiments may be made of this inventive concept, and as many modifications may be made in the embodiments hereinbefore shown and described, it is to be understood that all matter herein is to be interpreted merely as illustrative, and not in a limiting sense.

I claim:

1. In a foundation garment, the combination of a pair of identical but opposite elastic panels, at least one elastic reinforcing strip extending diagonally across the full extent of each panel, each panel being provided at an intermediate point with a substantially vertical fold line dividing the panel into a main panel and an extending tongue, with a portion of the strip extending across the tongues, each of the tongues being reverted along its associated fold line to dispose the extending portion of its associated strip in acute angled relation to that portion of the strip extending across the main panel, said panels being stitched together along said reverted fold lines whereby the composite garment portion is provided with a center section of double thickness providing maximum resistance and characterized by reverted abutting elastic reinforcing strips extending symmetrically on opposite sides of said stitched together fold lines.

2. The structure of claim 1 wherein said panels are front panels.

3. The structure of claim 1 wherein said panels are rear panels.

4. The structure of claim 1 wherein two pairs of panels are provided, one pair comprising the rear of the garment and the other pair, the front of the garment.

5. The structure of claim 1 wherein two pairs of panels are provided, each pair comprising one side of the garment with the fold lines stitched together on the sides with the edges opposite the fold lines being stitched together at the center of the front and rear of the garment.

6. The structure of claim 1 wherein at least two strips are provided in non-parallel relation.

7. The structure of claim 1 wherein the diagonal strips extend from a point adjacent the top of the garment to a substantially central point on said tongue.

8. The structure of claim 1 wherein the diagonal strips extend from a point adjacent the bottom of the garment to a substantially central point on said tongue.
